217,907

COMBINED TRUNK AND STORAGE TANK FOR AUTOMOBILES

Frank W. Derenski, 11009 Morrison St.,
North Hollywood, Calif. 91601

Filed Dec. 16, 1968, Ser. No. 14,991

Term of patent 14 years

Int. Cl. D12—14

U.S. Cl. D14—27

Fig. 1

Fig. 2

Fig. 4

Fig. 3

FIG. 1 is a side elevation;
FIG. 2 is a perspective view;
FIG. 3 is another side elevation;
FIG. 4 is a front elevational view thereof;
The automobile shown fragmentarily in broken lines in
FIG. 1 is included for illustrative purposes only.
The side opposite to that shown in FIGS. 1, 2 and 3
is a mirror image thereof.

I claim:

The ornamental design for combined trunk and storage
tank for automobiles, as shown and described.
